Inventor

UNITED STATES PATENT OFFICE.

ARTHUR H. WESTON, OF NEW YORK, N. Y., ASSIGNOR TO THE T. H. SYMINGTON COMPANY, OF NEW YORK, N. Y., A CORPORATION OF DELAWARE.

DRAFT RIGGING.

Application filed April 30, 1921. Serial No. 465,727.

To all whom it may concern:

Be it known that I, ARTHUR H. WESTON, a citizen of the United States, residing at New York, in the county of New York and 5 State of New York, have invented certain new and useful Improvements in Draft Rigging; and I do hereby declare the following to be a full, clear, and exact description of the invention, such as will 10 enable others skilled in the art to which it appertains to make and use the same.

The invention relates to draft rigging and more particularly to cheek plates or stop castings therefor.

15 The principal object of my invention, broadly stated, is to strengthen and improve the form of cheek plates now employed in connection with the Farlow draft rigging. To this end I provide a cheek 20 plate adapted to be applied to the outer face of a draft or center sill, the said plate having a continuous inwardly projecting lip or boss which is adapted to extend within a continuous slot in the said sill, the 25 said lip or boss projecting inwardly beyond the inner face of the sill and having its intermediate portions connected so as to reinforce the abutment interposed between the adjacent ends of the slots within said 30 cheek plate.

Another object of the invention is to provide a cheek plate for use in connection with draft or center sills having therein a continuous elongated slot, the said cheek 35 plates being provided with a plurality of key receiving slots the marginal edges of which are defined by lateral projections, the lateral projections on one face of the cheek plate being adapted to extend within 40 the slot in the sill beyond the inner face of the latter, the reinforcement extending around the adjacent ends of the slots in the said cheek plates being extended laterally on both sides of the web of the cheek plate 45 so as to form a broad bearing for the coupler key and the follower key on movements of the draft rigging in opposite directions from normal.

To these and other ends the invention 50 comprises the various elements and combinations of elements as hereinafter set forth.

In the drawings,—

Figure 1 is a transverse longitudinal sectional view of a portion of a car under- 55 frame partially in top plan showing the in-

vention embodied in a railway draft rigging.

Figure 2 is a view in side elevation of my improved form of cheek plate.

Figure 3 is a central longitudinal sectional view of Fig. 2.

The numerals 1, 1 designate the center or draft sills of a railway car, and 2 is the combined tie plate and stop casting which is adapted to be interposed between and 60 rigidly connected to the said sills by means of rivets 3, 3. Adjacent the forward ends of the sills are provided the cheek plates or stop castings 4, 4 hereinafter more fully described. The yoke member 5 by which 70 the coupler 6 is operatively connected to the cushioning mechanism 7, the latter being diagrammatically illustrated by dot and dash lines 8, is adapted to normally bear at its inner end against the face of 75 the stop casting 2. Intermediate the coupler 6 and the cushioning mechanism 7 there is provided a slotted follower block 9, and passing through slots in the coupler 6 and the follower block 9 are the transversely 80 extending keys 10 and 11, respectively. Normally the key 10 extends through the slots 12 in the yoke 5 and is adapted to bear at its forward edge against the forward edges of the said slots 12. As will be ob- 85 served from the drawings, the slots 12 are elongated rearwardly of the key so as to permit the key and coupler to move rearwardly independently of the yoke when the coupler is moved toward the back stop casting 2 under 90 a buffing blow or load. Similarly the key 11 is adapted to extend through the elongated slots 13 in the yoke 5 and preferably is in normal position slightly spaced from the forward ends of the said slots 13. The 95 slots 13 are also elongated so as to permit the inward or rearward movement of the follower independent of the yoke 5 on buffing movements of the coupler.

The cheek plates 4 are provided with a 100 web 14 which is preferably perforated at 15 to receive rivets or other connecting means 16 which serve to connect the cheek plates to the center or draft sills 1. The sill adjacent the face of each cheek plate is provided with a continuous lip or flange 17 which defines the edges of the slots 18 and 19 in the said cheek plate. The central portion of the said lip 17 is laterally extended as at 20 so as to 105 increase the inward projection of the said 110

lip or flange, and preferably the central portion of said lip or flange is connected adjacent the ends of the said slots 18 and 19 as clearly shown at 21 in Figs. 1 and 3. On the outer face of the cheek plate 4 and surrounding the slots 18 and 19 there is provided a lip or flange 22 which may be and preferably is of uniform depth or height. The said lip or flange 22 may be considered as extending around the outer ends of the slots 18 and 19 and as defining the horizontal edges of the slots and connected at the central portion by means of a filler 23, or the flange 22 may be considered as defining the edges of the said slots and connected at top and bottom by means of flanges or extensions which for convenience are a part of the filler 23. In other words, at the adjacent ends of the slots 18 and 19 and on opposite sides of the web there are provided laterally extending flanges which are connected in line with the upper and lower edges of said slots by the continuation of the respective flanges 17 and 22 which surround the said slots on opposite sides of the cheek plate.

By providing a continuous slot within the center or draft sills 1, and by furnishing each cheek plate with an inwardly extending flange which extends beyond the inner face of the center sill and by tying the flanges together as hereinbefore described, I avoid the necessity of providing a plurality of spaced slots within the center sill and greatly simplify the assembly of the cheek plates with the sill and at the time materially increase the strength of the cheek plate and adequately reinforce the draft sill to compensate for the metal taken therefrom. In addition to the foregoing I am enabled by this construction to accurately position the cheek plates directly opposite each other with a minimum amount of labor.

I claim:-

45. 1. A cheek plate comprising a web having a plurality of aligned slots therein, flanges projecting laterally from the opposite faces of said web and defining the edges of said slots, and means projecting from said web for connecting the flanges on each face of the web at the adjacent ends of said slots.
50. 2. A cheek plate adapted for connection to a draft sill, said plate comprising a web having a plurality of horizontally aligned slots therein, a plurality of flanges projecting laterally from the opposite faces of said plate, said flanges defining the edges of the said slots, and means for connecting said flanges adjacent the adjoining ends of said slots.
55. 3. In a draft rigging, the combination with center sills each of which is provided with an elongated slot therein, of cheek-plates having a plurality of aligned slots therein and connected to the outer faces of

said sills, flanges projecting laterally from the opposite faces of each cheek-plate, the sill adjacent portions of said flanges being adapted to extend through the respective slots in each sill, said flanges extending continuously from end to end of said sill slot.

4. In a draft rigging, the combination with a pair of draft sills each provided with a longitudinally extending slot therein, of cheek plates connected to the outer faces of said sills and each provided with a plurality of slots therein, flanges projecting from the opposite faces of each cheek plate, said flanges defining the edges of the said slots and the sill adjacent flange of each cheek-plate respectively extending within and through the adjacent slot in the said sills.

5. In a draft rigging, the combination with a horizontally arranged yoke, of a coupler connected thereto, center sills each of which is provided with an elongated slot, cheek-plates having a plurality of slots therein, said plates being connected to the outer faces of the said sills, and flanges defining the edges of the cheek-plate slots and extending respectively from the opposite faces thereof, the sill adjacent flanges of each cheek-plate being adapted to extend within and through the slot in the adjacent sill, the intermediate portions of said flanges lying parallel to the adjacent face of the said yoke.

6. A cheek plate having a body web affording means for securing it to the center sill or draft sill of a car, and having a plurality of key receiving slots adapted to register with a continuous slot formed in said car sill, and being provided on opposite sides of said web with flanges respectively bordering the said slots of the cheek-plate, and also being provided with a portion integrally uniting said flanges on the inner side of said cheek-plate and adapted to project through the slot in the car sill.

7. A cheek plate having a body web affording means for securing it to the center sill or draft sill of a car, and having a plurality of key receiving slots adapted to register with a continuous slot formed in the car sill, and being provided on its inner side with flanges respectively bordering the slots of said cheek plates, and also being provided with a portion uniting said flanges and adapted to project through the slot in said sill.

8. A cheek plate having a body web affording means for securing it to the center sill or draft sill of a car, and having a plurality of key receiving slots in said web which are adapted to register with a continuous slot in the car sill, and being provided between opposite ends of said slots with a tapering flange portion adapted to project through the said slot in the said sill.

9. A cheek plate having a body web af-

fording means for securing it to the center sill or draft sill of a car, and having a plurality of key receiving slots adapted to register with a continuous slot formed in 5 the car sill, and being provided on one side of said web with flanges respectively bordering the slots of said cheek plate, the projection of one of said flanges from said web being of greater extent adjacent the neighbor- 10 boring ends of the slots in said cheek plate.

10. A cheek plate having a body web affording means for securing it to the center sill or draft sill of a car, and having a plurality of key receiving slots adapted to 15 register with a continuous slot formed in the car sill, and being provided with flanges bordering the adjacent ends of its slots and adapted to project through the slot in the sill, and also being provided with a web integrally uniting said flanges to said body 20 web and adapted to extend into the said slot in the sill.

11. A cheek plate having a body web affording means for securing it to the center sill or draft sill of a car, and having a 25 plurality of key receiving slots and being provided on the inner side of said web with flanges respectively bordering said slots, the projection of one of said flanges from said web being of greater extent adjacent to the neighboring ends of the slots.

12. A cheek plate having a body web affording means for securing it to a center sill or draft sill of a car, and having a key receiving slot adapted to register with a 35 slot in the web of said sill and being provided on opposite sides of said body web with flanges bordering the said slot of the cheek plate, one of said flanges extending through the web of said sill and gradually 40 increasing in width intermediate the ends thereof.

In testimony whereof I affix my signature.
ARTHUR H. WESTON.
